UNITED STATES PATENT OFFICE.

PERCY SLOPER, OF LONDON, ENGLAND.

BURNER FOR BURNING OIL FUEL.

Application filed September 8, 1924. Serial No. 736,565.

To all whom it may concern:

Be it known that PERCY SLOPER, a subject of the King of Great Britain, residing at London, England, has invented certain new 5 and useful Improvements in Burners for Burning Oil Fuel, of which the following is a specification.

This invention relates to pressure or gravity fed burners for burning oil fuel, 10 paraffin and other liquid fuels, especially heavy oils such as are used in ranges, furnaces, boilers and for other purposes, and to that class of burners in which the fuel oil and air or gas meet just inside the outlet 15 nozzle through which the mixture passes for burning, and has for its object to construct such a burner wherein the oil is perfectly atomized and which is economical and reliable in use, especially when the burner is 20 turned down to reduce the size of flame and heating power.

According to this invention I construct the burner in such a manner that the oil emerges into the nozzle from two tubes or 25 holes in the same plane, and the air or steam necessary for combustion issues from two tubes or holes in another plane and equidistant between the oil tubes or holes. It is important for the proper working of the 30 burner that the length of the air or steam passages from the controlling valve to the outlet be of exactly the same length and also that the two oil passages should also be of the same length.

35 My invention will be clearly understood from the following description aided by the annexed drawings which illustrate one example of carrying my invention into effect and in which Figure 1 is a sectional plan, 40 Figure 2 an elevation, Figure 3 a front view (turned through 90° to Figure 1) of a burner and Figure 4 a side view and Figure 5 an end view of a detail on an enlarged scale.

45 In my preferred construction of burner shown on the annexed drawings I employ a casting 1 in which is formed the oil inlet 2 for connection to the oil reservoir. The inlet 2 is controlled by a needle valve 3 and leads to a passageway 4 which branches out 50 into two passageways 5 at an angle to one another. The passageways 5 pass to the front of the casting 1 and discharge upon a flat portion or seat 6 at the base of a depression formed in the front portion of said casting, the discharge ends of the passage-

ways 5 being in the same plane drawn through the axis of said depression, and such passageways 5 being of exactly the same length from the needle valve seating 7 60 to their outlets in the flat portion 6.

In the casting 1 is also formed the compressed air or steam inlet 8 controlled by another needle valve 9, this inlet leading to a passageway 10 which branches out into 65 two passageways 11 at an angle in a similar manner to the oil passageways 5, and such passageways 11 are so arranged that they open on the flat portion 6 in a vertical line at equal distances between the openings of 70 the oil passageways 5. These passageways 11 are exactly the same length from the needle valve seating 12 to the outlets in the flat portion 6.

Secured to in the recess of the casting 1 75 against the flat portion or seat 6 by a screw ring 13 or other means is a tube 14 in which is positioned a metal cylinder 15 having its forward end 16 coned or curved with the point flattened or cut off as at 17 (Figure 80 4) and through the cylinder 15 are formed four longitudinal passageways 18, 18, 19 and 19 so positioned that when the member 15 is inserted in the tube 14 and its flat rear 85 end positioned against the flat portion or seat 6 of the casting 1, the passageways 18, 18 will coincide with the oil passageways 5, and the passageways 19 will coincide with the air or steam passageways 11 in the casting 1. The passageways 18, 18 and 19, 90 19 pass through the member 15 and terminate at the coned end 16. Grooves 20, 20 and 21, 21 or recesses are formed in the coned end 16 leading from the passageways 18, 18 and 19, 19 to the flattened end 17.

Locating pins 22, 23 are preferably formed, respectively, at the rear end of the tube 14 and at the rear end of the member 15 to engage, respectively, in recesses formed in the flat portion or seat 6 of the 95 casting 1 and in the rear end of the tube 14, to ensure that the tube 14 and member 15 are properly positioned on the flat portion 6.

On to the forward end of the tube 14 is secured the burner nozzle 24, the rear or inner side of which is coned to correspond with the cone 16 on the member 15, and through the centre of said nozzle 24 is formed a hole 25 which acts as the outlet for the air or steam and oil. I have found that 100 by varying the thickness of the metal of the nozzle 24 at that part through which the

hole 25 passes, and consequently the length of the hole 25, I can vary the position of the point where the oil is burnt from the burner 24.

5 The flattened end 17 of the member 15 is larger in diameter than the hole 25 and a small space is left between said end and that portion of the nozzle within which it fits, which space is equivalent to the point of the 10 cone 16. In the space just mentioned the oil and air or steam mix and are immediately ejected through the hole 25 in the burner nozzle 24.

26 is a washer between the rear end of the 15 member 15 and the flat portion or seat 6 and 27 a gauze strainer.

The oil and air or steam do not meet until they reach the space between the flattened end 17 of the member 15 and the inside of 20 the burner nozzle 24 and then immediately pass through the hole 25 to the outside for burning. By making the length of the 25 passageways 11 for the air or steam of exactly the same length, and also the passageways 15 for the oil of exactly the same length perfect economical burning of the oil without drip is obtained, especially when either the valve 3 or the valve 9, or both of them, are partially closed for reducing the 30 heating power of the burner.

The member 15 has a flange at its rear end which, when the burner is assembled, fits in a similarly-shaped depression formed in the rear end of the sleeve 14. The member 15 is thus held in place in the depression of the casting against the flat portion or seat 6 by the sleeve 14, which sleeve is, in turn, held in place by the screw ring 13.

It will be understood that various detail 40 alterations can be made in the construction of the burner without departing from the spirit of my invention.

What I do claim as my invention and desire to secure by Letters Patent is:—

45 1. An oil burner comprising a casting having a seat at its forward end and having an oil inlet and a plurality of passages extending from said oil inlet to said seat, said casting also having an inlet for a combustion-supporting gas and a plurality of passages extending from said latter inlet to said seat at points equidistant from the points of discharge of said oil-inlet passages, a member having its rear end bearing 50 against said seat and having its forward end formed as a truncated cone, said member also being formed with a plurality of passages having their rear ends aligning with the outlet ends of said oil-inlet passages 55 and of said gas-inlet passages and having their forward ends terminating in the conical part of the forward end of said member, and a burner nozzle secured to said casting in advance of the forward end of said 60 member, said nozzle having a conical recess 65

shaped to substantially conform with and to receive the forward end of said member and having a discharge passage co-axial with said conical recess.

2. An oil burner comprising a casting 70 having at its forward end a circular depression of which the base forms a flat seat, said casting having an oil inlet and a plurality of passages extending from said oil-inlet and terminating in said flat seat, said casting also having an inlet for a combustion-supporting gas and a plurality of passages extending from said last-named inlet and terminating in said flat seat at points equidistant from the outlets of said oil-inlet 80 passages, a cylindrical member of smaller diameter than said circular depression having its rear end flattened and bearing against said flat seat and having its forward end formed as a truncated cone, said cylindrical member also having a plurality of longitudinal passages of which the rear ends align with the outlet ends of said oil and gas passages and the forward ends terminate in the conical part of the said member, a sleeve surrounding said member and having its rear end resting against the base of said circular depression, said sleeve having means associated with said casting and with said cylindrical member to maintain the passages 90 of the latter in alignment with the outlet ends of said oil and gas passages, and a burner nozzle secured to the forward end of said sleeve, said burner nozzle having a conical depression shaped to substantially conform with and receive the forward end of said cylindrical member and also having a discharge passage co-axial with said conical recess.

3. An oil burner according to claim 1 105 wherein the truncated cone-shaped forward end of the member is formed with longitudinal grooves with each of which one of the passageways of said member communicates.

4. An oil burner according to claim 1, 110 wherein the passages from the oil-inlet to the seat of the casting are of equal length and the passages from the gas-inlet to the seat of the casting are of equal length.

5. An oil burner according to claim 2, 115 wherein the rear end of the sleeve engages the cylindrical member adjacent the rear end of the latter and wherein means associated with said sleeve and with said casting secures said cylindrical member in place.

6. An oil burner according to claim 2 120 wherein the burner nozzle is detachably connected to the forward end of the sleeve.

In testimony whereof I have hereunto set my hand in the presence of two subscribing witnesses.

PERCY SLOPER.
